UNITED STATES PATENT OFFICE.

HUDSON MAXIM, OF NEW YORK, N. Y.

HIGH-EXPLOSIVE COMPOUND AND PROCESS OF MAKING SAME.

SPECIFICATION forming part of Letters Patent No. 792,716, dated June 20, 1905.

Application filed January 29, 1903. Serial No. 141,065.

To all whom it may concern:

Be it known that I, HUDSON MAXIM, of 891 Sterling Place, Brooklyn, county of Kings, city and State of New York, have invented a new and useful Improvement in High-Explosive Compounds, which invention is fully set forth in the following specification.

The present invention relates to improvements in high-explosive compounds, as bursting charges for projectiles.

The object of the invention is mainly to produce a high explosive and by an improved process of manufacture which shall be so insensitive to percussion as to enable it to withstand the shock of penetrating armor-plate and an explosive which may be melted or fused over an ordinary water-bath and poured into shells in a fused state, and an explosive also which shall on cooling expand slightly and set firmly upon and adhere to the walls of the projectile, and an explosive also which shall be stable, non-hygroscopic, and capable of being stored for any length of time under various climatic conditions without undergoing chemical change.

I have discovered that although the melting-point of picric acid is 122° and that of dinitro-phenol is 113° to 114° centigrade, if the two be mixed the common melting-point is reduced to about 69° centigrade, varying slightly with the relative proportion of the ingredients. This phenomenon is due to the mutual chemical affinity of the two homologous substances, which gives them a mutual tendency to enter into solution for the purpose of more intimate union in exactly the same manner that a mixture of ice and salt will combine to form a liquid at a temperature below that at which the ice normally remains a solid.

Picric acid contains one atom of oxygen more than it contains of carbon, the formula being $C_6H_3N_3O_7$, while dinitro-phenol contains one atom of oxygen less than it contains of carbon, its formula being $C_6H_3N_2O_5$. Now, therefore, when picric acid is detonated in a strong steel shell with a powerful detonator, the carbon combines with the oxygen, producing carbonic acid, and as the temperature is too high at the instant of detonation for the

existence of the molecule of carbonic acid or the water molecule the products of combustion consist of carbonic acid, free nitrogen, and free hydrogen, together with any oxygen in a free state which may be in excess of that necessary to the production of carbonic acid.

I have found by experiment that when the carbon content of the explosive is equal or slightly in excess of the oxygen content the sensitiveness of the explosive is very much diminished, while theoretically that explosive which shall produce the highest results as a shattering agent is one in which there is an equal quantity of both carbon and oxygen, and practice has confirmed this theory. Consequently I have found that a compound consisting of about fifty-two parts, by weight, of picric acid and forty-eight parts, by weight, of dinitro-phenol, and one in which the quantities of carbon and oxygen balance each other, forms the most favorable compound for my purpose. I may of course vary the proportions of this compound within wide limits without departing from the invention. For example, for filling projectiles for quick-firing guns—that is to say, projectiles of from one to six inches in caliber—a larger percentage of picric acid and a smaller percentage of dinitro-phenol is preferred, for the reason that the shock upon the explosive both in the gun and upon armor-plate is not so great in small shell as in large shell, and it is not so practical to employ in such small shell an exploder sufficiently powerful for the detonation of an explosive so insensitive as is required in projectiles from six to twelve inches in caliber, while for field-shell of all calibers there is not required such an insensitive compound as that necessary to be employed against armor-plate.

In carrying out the invention I preferably prepare the picric acid and the dinitro-phenol separately, and before washing to free of acid and to purify they are mixed in the proportions required for the final product—say in the proportions of about fifty-two parts picric acid to forty-eight parts dinitro-phenol, and the mixture is then washed in warm water, or water at a temperature slightly above the fusion-point of the compound. By this

means a great advantage is secured and much time saved on account of the advantage of being able to wash the compound in a liquid state and with water. After washing the supernatant liquid is allowed to cool to allow the explosive compound held in solution when hot in excess of what the water will hold when cold to crystallize from solution. This process of washing may be repeated with additional water until the compound is entirely purified. Neutralizers may also of course be employed, if desired, to assist in the elimination of any free nitric or sulfuric acid.

What is claimed is—

- 15 1. The process of purifying an explosive compound, which consists in combining two nitro compounds, one or both of which has a melting-point above the boiling-point of water, to produce an explosive compound having a melting-point below the melting-point of water, and then washing with water of a temperature at or above the fusion-point of the explosive compound.
- 20 2. The process of purifying an explosive compound, consisting of uniting two or more nitro compounds, each having a melting-point above the boiling-point of water, to form an explosive compound having a melting-point below the boiling-point of water, and washing the explosive compound in a state of fusion with water of a temperature at or above the melting-point of the explosive compound.
- 25 3. The process of making an explosive compound, consisting in heating a mixture of

picric acid and dinitro-phenol in presence of water to a temperature below the melting-point of each ingredient to melt the said mixture, and then washing the same in water.

4. The process of making an explosive compound, consisting in heating a mixture of about fifty-two parts picric acid and forty-eight parts dinitro-phenol in presence of water to a temperature below the melting-point of each ingredient to melt the said mixture, and then washing the same in water.

5. The process of making an explosive compound, consisting in heating a mixture of picric acid and dinitro-phenol in presence of water to a temperature below the melting-point of each ingredient to melt said mixture, washing the same in warm water and then cooling said wash-water to separate out the explosive compound held in solution.

6. An explosive compound, consisting of picric acid and dinitro-phenol associated in solution with each other, the carbon and oxygen in said mixture being substantially in the ratio of their atomic proportions and the melting-point of the compound being less than that of either of said ingredients.

In testimony whereof I, HUDSON MAXIM, have signed this specification in the presence of two subscribing witnesses.

HUDSON MAXIM.
